CLAIM

The ornamental design for a faucet, as shown and described.

DESCRIPTION

FIG. 1 is perspective view of a faucet incorporating my new design, viewed from in front of, above, and from the left side of the faucet and shown in combination with the remainder of a faucet with which it is usable;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a left-side elevation view thereof with the right side being a mirror image of the left side.

The broken lines in FIG. 5 are for illustrative purposes only and form no part of the claimed design.

1 Claim, 6 Drawing Sheets
